UNITED STATES PATENT OFFICE.

FERNANDO JIMENEZ, OF MANILA, PHILIPPINE ISLANDS.

DESIGN FOR AN INDICATOR.

60,617.

Specification for Design. Patented Mar. 14, 1922.

Application filed July 25, 1921. Serial No. 487,557. Term of patent 14 years.

To all whom it may concern:

Be it known that I, FERNANDO JIMENEZ, a citizen of Manila, Philippine Islands, residing at Manila, Philippine Islands, have invented a new, original, and ornamental Design for an Indicator, of which the following is a specification, reference being had to the accompanying drawings, forming a part hereof.

The figure is a perspective view showing my new design.

I claim:

The ornamental design for an indicator as shown.

FERNANDO JIMENEZ.

Witnesses:

PEDRO SUPE,
E. McGLEQUIN.
